ATTORNEY.

UNITED STATES PATENT OFFICE.

THEODORE G. JOHNSON, OF KANSAS CITY, MISSOURI.

DUST-MOP.

1,134,984.

Specification of Letters Patent.

Patented Apr. 6, 1915.

Application filed June 1, 1914. Serial No. 842,077.

To all whom it may concern:

Be it known that I, THEODORE G. JOHNSON, a citizen of the United States, residing at Kansas City, in the county of Jackson and State of Missouri, have invented certain new and useful Improvements in Dust-Mops, of which the following is a specification.

My invention relates to improvements in mops, and one object is to provide a mop which can be readily placed in position upon a mop-head or quickly removed therefrom.

A further object is to provide a mop which will inclose the mop-holder head, so that the latter cannot come into direct contact with and scratch mop-boards, furniture, etc.

A further object of the invention is to provide a well-made, durable, mop which may be used to advantage not only in cleaning and polishing floors, but also walls and ceilings as well.

While I am not to be understood as restricting the use of my mop with any particular type of holder, it may be used to advantage on the holder disclosed in my co-pending application filed May 14, 1913, and bearing Serial No. 767,583.

In order that the invention may be fully understood, reference will now be made to the accompanying drawing, in which:

Figure 1 is a perspective view of the mop open and ready to apply to a mop-holder. Fig. 2 is a plan view of the mop closed as when applied to a mop holder. Fig. 3 is a cross section on line III—III of Fig. 2. Fig. 4 is an inverted plan view of a main piece of fabric constituting a part of the mop. Fig. 5 is a plan view of a top piece of fabric forming a part of the mop.

In carrying out the invention, I employ a main piece of fabric 1, of substantially triangular conformation in plan view, and provided with a rearwardly extending tongue 2.

3 designates a supplemental or top piece of fabric of the general conformation of the main piece of fabric 1, upon which it is firmly secured by marginal stitches 4. The top piece 3 and the main piece 1, are, preferably, made of canvas and when sewed together, as described, form a pocket 5 to receive the mop-holder head, not shown. An opening 6 extending forwardly from the rear end of the top piece 3, is formed in the latter to permit the bale of the mop holder handle to swing back and forth. The tongue

2 and the top piece 3, are provided with an adjustable fastening device consisting of a

pivotal member 7 fastened to the rear end of the tongue 2, and a slotted member 8 secured to the top piece 3 at the forward end of the opening 6. When the tongue 2 is folded forward, as disclosed by Fig. 2, to cover the rear end of the mop head, said tongue is reliably secured in said folded position by passing the member 7 through any of the slots in the member 8.

9 designates a cord or tape which is sewed to the top piece 3, around which it extends near the margin thereof, for the purpose of securing cotton cord 10, or other soft material, to said top piece 3. The cotton cord 10 is of sufficient length to overhang the stiff margins of the main piece 1 and the top piece 3, to prevent said stiff margins from coming into direct contact with mop-boards and furniture. The ends of the tape 9, extend a sufficient distance beyond the rear ends of the top piece 3 to permit their being tied together, as indicated by the dotted lines, Fig. 2, to prevent the rear ends of the pocket 5 from spreading apart when the mop is in position upon a mop-head. The bottom of the main piece 1 is provided with rows of cotton cord 11, or other soft material, which is firmly held in place by strips of tape 12, extending longitudinally and transversely of the main piece 1, to which they are firmly secured by stitches 13. The strands of the cotton cord 10 and 11 are engaged intermediate their ends by tapes 9 and 12, over which they hang, as disclosed by Fig. 3, so that they cannot be pulled out of place.

From the foregoing description, it is apparent that I have produced a mop embodying all the features of advantage above enumerated, and while I have shown and described the preferred form of my invention, I of course, reserve the right to make such changes in the construction, combination and arrangement of parts as properly fall within the spirit and scope of the claims.

Having thus described my invention, what I claim and desire to secure by Letters Patent, is:

1. A mop consisting of a main piece of fabric having a tongue extending rearwardly therefrom, a fastening device secured to said tongue, a top piece of fabric secured to said main piece of fabric to form a pocket, a fastening device on said top piece to coact with the first-mentioned fastening device in securing the mop to a mop holder head, and

soft material secured to the main piece of fabric.

2. A mop consisting of a main piece of fabric, a top piece of fabric secured to said main piece of fabric to form a pocket for the reception of a mop holder head, a tape extending around the top piece near the margin thereof, cotton cord secured to the top piece by said tape and adapted to overhang the margin thereof, and soft material secured to the underside of the main piece of fabric.

10 hang the margin of said top piece, and soft material secured to the underside of the main piece of fabric.

3. A mop consisting of a main piece of

fabric, a top piece of fabric secured to said main piece of fabric to form a pocket for 15 the reception of a mop holder head, soft material secured to said top piece and adapted to overhang the margin thereof, and soft material depending from the underside of the main piece of fabric.

20 In testimony whereof I affix my signature, in the presence of two witnesses.

THEODORE G. JOHNSON.
